UNITED STATES PATENT OFFICE

WILLIAM SCHWALGE, OF ELMHURST, ILLINOIS

DEVICE FOR SEPARATING GASOLINE FROM LUBRICATING OILS

Application filed May 11, 1926. Serial No. 108,347.

This invention relates to a method and device or apparatus for separating gasoline or similar volatile fluids from lubricating oils after being used, such as in the crank case of 5 an automobile or the like.

An object of the invention is to recover the oil in a cheap and efficient manner and permit the gasoline or other volatile oils or material to be separated and passed off in the form of 10 vapor or fumes and to provide a portable electrically heated device for this purpose.

Another object of the invention is also to provide novel means for distributing the used or lubricating oil over a surface so that less 15 heat is required to separate oils from the grease or lubricating oils and to distribute or spread the same in the form of a thin film or layer whereby the separating action is greatly expedited and enhanced, and a clear 20 amber colored product produced from a used lubricating oil containing carbon and other impurities as well as solid constituents.

Other and further objects will be apparent 25 as the description proceeds.

In the accompanying drawings:

Figure 1 is a perspective view of a portable 30 electrically heated device or apparatus for separating gasoline or other volatile oils from lubricating oils and for carrying out my novel method.

Figure 2 is a plan view of the device or apparatus.

Figure 3 is an enlarged transverse sectional view across the center of the device 35 showing the upper portion with the heaters and spreaders.

Figure 4 is an enlarged central longitudinal sectional view of the device, and

Figure 5 is an enlarged detail perspective 40 view of one of the spreaders or distributors constituting a part of the device.

Referring to the drawings in detail, in 45 which like reference characters designate corresponding parts throughout the several views, the device is shown as comprising a casing 5 preferably of metal and rectangular cross section and shape supported on legs 6 if desired, said casing having an opening 7 across the bottom of the front wall. The 50 top portion 8 is preferably disposed on a

slight incline or adapted to support in a slightly inclined position, a relatively shallow pan 9 having a surrounding rim 10 adapted to rest on the top edge 8, which latter has its sides preferably flanged or directly inwardly at right angles, as indicated at 11. The ends 55 of the pan 9 are disposed very close to the ends of the casing 5, being substantially in contact therewith as shown in Figure 4, while the sides are directed outwardly to form flanges 12 supported on the inwardly extended flanges 11 and providing air spaces 13 between the sides of the pan and the sides of the casing, as clearly shown in Figure 3 of the drawings.

Arranged over the top of the casing is a cover 14 having one or more escape openings 15 over which may be provided a ventilating pipe or chimney 16 for the escape of the fumes or vapors as will be later described. At 70 one end of the casing, a suitable bracket or support 17 is provided for a reservoir or tank 18, the supply or feeding of the oil therefrom being regulated by a faucet or cock 19 from which it is discharged onto the 75 inclined plane or pan 9.

Pan 9 is provided at opposite sides with openings 20 preferably of semi-circular form as shown extending from the top edge thereof 80 partially into the sides, that is spaced from the bottom of the pan to prevent the oil from flowing thereover, but permitting free circulation of air through the passages or channels 13 between the sides of the pan and the sides of the casing through the openings 20 85 and above the pan, the same finally making exit through the escape opening or chimney 16. The lower portion of the pan or partition formed thereby in the casing, is provided to drain the oil towards the center, at which 90 point it is provided with an outlet pipe or spout 21 through which the refined and amber colored oil is delivered into a receptacle 22 after the gasoline or other volatile products are separated therefrom.

A series of gas baffles and spreaders or distributors 23 are arranged transversely across the partition or bottom of the pan 9 and these spreaders are preferably made in the form of obtuse angled members or plates, all of the 100

parts being preferably of galvanized sheet metal, or the like. These plates are open at their ends and are bent at suitable angles intermediately to form angular members so that 5 when the edges rest on the partition 9 formed by the bottom of the pan, substantially triangular chambers over the oil are provided, the form shown being of the cross section of a channel triangle. These spreaders have 10 oppositely sloping walls extending toward the partition 9 and they project slightly above the bottom edges of the openings 20 as indicated at 24, the spreaders being preferably arranged between opposite pairs of said openings 20 as shown. This provides escape openings 15 at the sides for air circulating in opposite directions beneath the spreaders or distributors so as to carry off the volatile gases or products of evaporation by air entering the opening 7 and then through the openings 20 from the side openings or passages 13. Obviously the air will also enter the sides of 20 spreaders and escape at the central openings 25 thereof, preferably of circular or other 25 form. The edges forming spreaders are suitably spaced apart in parallel relation or may be made to abut at their edges or stamped in one continuous piece arranged as shown in Figure 4, but are preferably made separate 30 and disposed in contact as indicated in Figures 4 and 5 arranged transversely of the pan or partition and are adapted to spread or distribute the oil to travel slowly in a thin film or sheet over the entire surface of the 35 bottom of the pan or partition 9 when the oil is poured onto the partition from the faucet or cock 19. The oil will then travel by gravity down to the escape opening or spout 21, the movement being slowly so as to permit the 40 oil to be confined with the gases and properly heated by suitable heating means arranged therebeneath for separating the gasoline and other volatile oils or products from the oil to escape as gas or fumes as heretofore pointed 45 out. In the form illustrated, electrical heating or resistance elements 26 are preferably provided for supplying the necessary heat and these elements preferably comprise cores 27 having the resistance wire or heating ele- 50 ment proper 28 wound thereon and anchored at each end as indicated at 29 and bars 30 provided on the end of rectangular form to engage angular brackets or supports 31 secured to the sides of the casing 5 as more clearly 55 shown in Figures 3 and 4 of the drawings.

Of course, the spreaders may be adapted to float slightly in order to permit the oil to escape and if desired may be serrated at the bottom edges or otherwise formed for this 60 purpose, but in the preferred construction, sufficient oil will pass beneath said spreaders owing to the irregularities of the metal and the effect of the oil and gases or fumes therebeneath, although comparatively smooth and 65 close fitting, as evidenced by the passage of

oil between a piston fitting substantially tightly within a cylinder, as appreciated by those acquainted with the art. The heater comprises a series of the heating elements connected to the end members 30, providing a single unit with the conductors 32 of the respective heating elements fitting into an extension cord 33 preferably properly insulated and mounted on an insulated bracket 34 at one side of the casing. This extension cord 33 is extended through an opening 35 in one side of the casing and has an attachment plug or other suitable connection 36 by which it may be connected to the house wiring or other electrical circuit to supply the necessary current for the heating elements. Obviously, the heating arrangement provided insures uniform heating entirely beneath the partition or bottom of the pan 9 but of course, any other suitable heating means may be provided 70 so long as excessive heating is guarded against. Furthermore, owing to the construction provided, the oil is not only heated from beneath the pan, but the heated air passes through the passages or openings 20 75 and is held down by the cover 14 so as to heat the oil, thus insuring quick and complete separation of the gasoline and other volatile products from the oil which is passed off and collected in an economically operated separating method. Thus, the gasoline or other line 80 of volatile oils contained in the lubricating oil will be separated therefrom and passed off in the form of a gas or vapor, the oil being collected in the receptacle 22 as shown. Obviously, the spreaders or distributors will obstruct the flow of the oil down the partition or heated plate and will spread the same in the form of a thin film or layer so as to secure 85 complete separation and slacken the speed of flow thereon through the outlet whence it is 90 delivered in the form of a clear usable oil. Of course, the oil may be previously treated under pressure in any preferred manner or well known way as by gravity separation, to 95 separate the gasoline and carbon matter from the heavy oil prior to the complete separation 100 accomplished by the present method and apparatus.

The heater 26 heats the oil to about 150° F. 115 and by the time it reaches the end of the inclined plane 9 the oil has reached the temperature about 250°.

While I have described my invention in a preferred form, it is also to be understood 120 that various modifications, and changes in the form, arrangement and construction as well as the proportion of the parts may be made without departing from the spirit and scope of the invention.

Having thus described my invention what I claim is:

1. A device for separating gasoline, volatile oils, and the like, from lubricating oils, comprising a casing, a pan supported by the 130

- member in a slightly inclined position, means for introducing oil into the pan at the top end thereof, spreader elements within the pan arranged to bound heating zones, limited by the spreaders on the top and two opposite sides and on the bottom by the pan, means for supplying heat to the zones, means for the escape of heated air and evolved vapors, an outlet in the pan for the discharge of separated oil therefrom, the spreaders being loosely mounted in the pan, a cover portion for the pan having an opening therein. 75
2. A device for separating gasoline from oil, comprising a main body portion, a pan supported thereon in a slightly inclined position, means for depositing oil within the pan, means for supplying heat to the pan, an outlet from the pan, a plurality of spreaders positioned within the pan, the spreaders comprising angularly formed members having open portions with their edges contacting with the pan, and ventilating openings for the circulation of air and the escape of the volatilized gases and separated products therein. 80
3. A device for separating gasoline from oil, comprising a pan, a cover for the pan, spreader members within the pan arranged to bound heating zones limited by the spreaders on top, and on the bottom by the pan, means for introducing oil into the pan, means beneath the pan for supplying heat, said pan, spreaders and cover having openings for the escape of heated air and evolved vapors, an outlet in one end of the pan for the discharge of oil therefrom. 85
4. A device for separating gasoline, volatile oils, and the like, from lubricating oils, comprising a casing, a pan supported by the casing in a slightly inclined position, a cover for the pan, spreader elements within the pan arranged to bound heating zones limited by the spreaders on the top and on the bottom by the pan, means beneath the pan for supplying heat to the zone, said pan, spreaders and cover having openings for the escape of heated air and evolved vapors, an outlet in the pan for the discharge of separated oil. 90
5. A device for separating gasoline, volatile oils, and the like, from lubricating oils, comprising a casing, a pan supported by the casing in a slightly inclined position, means for introducing oil into the top end of the pan, a cover for the pan, spreader elements within the pan arranged to bound heating zones limited by the spreaders on the top and two opposite sides and on the bottom by the pan, means beneath the pan for supplying heat to the zones said pan spreaders and cover having openings for the escape of heated air and evolved vapors, an outlet in the pan for discharge of separated oil, the spreaders being loosely mounted in the pan. 95
6. An apparatus of the class described, 100
